UNITED STATES PATENT OFFICE.

HAROLD P. DONLE, OF MERIDEN, CONNECTICUT, ASSIGNOR TO THE CONNECTICUT TELEPHONE & ELECTRIC COMPANY, INCORPORATED, OF MERIDEN, CONNECTICUT, A CORPORATION OF CONNECTICUT.

VARIABLE RESISTANCE.

Application filed May 20, 1925. Serial No. 31,522.

My invention relates to a variable resistance of the compression type.

It is the general object of the invention to provide an improved and simplified form of variable resistance of the compression type. The invention resides in certain combinations and details of construction hereinafter described.

Briefly stated, in the preferred form of the invention I employ a body of insulating material having a suitable recess therein for the reception of the compression resistance member. A wire terminal is electrically connected to one side of said resistance member and extends to the outside of the body member. A base plate and a face plate are positioned at opposite sides of the insulating body member and are electrically and mechanically connected together as by means of bolts. A screw or the like engaging a threaded sleeve on one of said plates serves to compress the resistance member and the bolts or other connecting links between the base plate and face plate serve to take the stress of the compression screw off of the insulating body member and causes that stress to be taken by said two plates and their mechanical connecting means. One of these cover plates is provided with a second wire terminal which is electrically connected with the opposite side of the resistance member. A spring may be employed for progressively applying the force of the compression screw to the resistance member and if desired a second spring may be employed for constantly urging the screw in one direction so as to take up the back lash. The entire device may be secured to a panel or the like by means of a single nut or by means of screws passing through ears on one of the cover plates.

In the drawings which show for illustrative purposes only, a preferred form of the invention:

Fig. 1 is a side view in elevation of a variable resistance embodying features of my invention;

Fig. 2 is a top plan view of the variable resistance shown in Fig. 1, a part being broken away;

Fig. 3 is a central sectional view taken substantially in the plane of the line 3—3 of Fig. 4;

Fig. 4 is a view taken substantially in the

plane of the line 4—4 of Fig. 3, parts being broken away.

In said drawings 5 indicates a body member of insulating material, this body being preferably provided with a recess or housing aperture 6 for the reception of parts to be later described. In the bottom of the housing there may be a metallic plate 7 connected as by means of a screw 8 to a wire terminal 9 extending to the outside of the housing for connection to a conductor. At the bottom of the body member is a base plate 10 insulated from the terminal member 9 as by means of an insulating disk 11 interposed between those parts. The base plate 10 may have a second wire terminal 12 integrally formed thereon. A face plate 13 fits on the body member and serves to close the recess 6. Connecting members such as bolts 14—14 pass through suitable passages in the body member and mechanically and electrically connect the two cover plates 10 and 13 to each other.

The face plate 13 may have a sleeve 15 secured thereto in any suitable manner and this sleeve is preferably threaded externally at 16 for the reception of the nut 17 for securing the entire assembly to a panel as will be clear from Fig. 1. The sleeve 15 is threaded internally for the reception of the compression screw 18 which extends through the sleeve and into the recess 6 in the body member. A knurled nut or the like 19 serves as a convenient means for rotating the screw for moving the same inwardly or outwardly.

A compression resistance member 20 is located in the recess 6 and is electrically connected at one side to the plate 7 and wire terminal 9. In the preferred form I interpose a plate 21 of silver plated brass or the like between the resistance member 20 and the plate 7 which latter plate may also be silver plated if desired. A second plate 22 of silver plated brass or the like preferably rests on top of the compression member 20. While it is not necessary to employ silver plates as herein described, it is quite desirable for the reason that the oxide of silver is itself a good conductor and, therefore, should the parts become oxidized the utility of the variable resistance would not be materially impaired.

I employ resilient means for effecting a progressively increasing pressure on the re-

sistance member by means of the screw 18. In the form shown a bowed spring 23 is interposed between the upper plate 22 and the screw 18. Now when the screw is moved inwardly the spring 23 is deflected and puts a progressively increasing pressure upon the resistance member and thus increases the distance through which the screw 18 and consequently the knob 19 must be rotated to produce the maximum compression of the resistance block. If the screw 18 acted directly upon the plate 22 the entire range of adjustment of the resistance would be a mere fraction of a turn of the screw 18.

Now in order to take up the back lash in the screw, a plate spring 24 may be seated on ledges 25—25 formed in the body member at opposite sides of the recess 6. This plate spring 24 acting beneath the screw 18 serves to constantly urge the same outwardly so that any back lash in the screw will be taken up, thus reducing to a minimum the variation of the instrument.

The operation of the device will now be clear. The entire assembly may be secured on a panel as by means of the nut 17 as clearly shown in Fig. 1, or if desired, the base plate 10 may have ears 26—26 for receiving screws or the like for positioning the assembly on a suitable base. When the screw 18 is moved inwardly the plate spring 24 takes up the back lash and the screw in moving inwardly stresses the spring 23 which in turn acts on the plate 22 so as to compress the resistance member 20.

In devices of this character the conductivity is determined by the extent of compression of the resistance member. The current flow through the device may be through the terminal 9, screw 8, plate 7, plate 21, resistance member 20, plate 22, springs 23 and 24, screw 18 to the face plate 13. From the face plate 13 current is conducted through the bolts on other connecting members 14 to the base plate 10 and thence to terminal 12.

It will be seen that in a construction as herein described considerable force is exerted on the compression member and supporting parts by the screw 18. It is, therefore, quite desirable to have the base plate 10 and the face plate 13 connected to each other as by means of the bolts 14 as by this construction substantially the entire force of the screw 18 is taken by the two cover plates and the screws 14 and the insulating body member is not substantially stressed.

The resistance member may be made so as to

give the desired range of the instrument and one or more blocks or plates may be employed if desired though it is preferred to employ a single block and to vary the composition of the block for securing different ranges.

While the invention has been described in detail, I do not wish to be confined to the specific form shown since changes may be made within the scope of the invention as defined in the appended claims.

I claim:

1. In a device of the character described, an insulating body member, a metallic base plate at one side thereof, a metallic face plate at the opposite side, said body member having a recess therein, a resistance member in said recess, bolts extending through said insulating body member at opposite sides of said resistance member for electrically and mechanically connecting said plates to each other and means for compressing said resistance member, a terminal electrically connected to one side of said resistance member and a terminal electrically connected to the opposite side of said resistance member through said bolts for connecting said base and face plates.

2. In a device of the character described, an insulating body member having a recess therein, said body member having supporting ledges at opposite sides of said recess, a compression resistance member in said recess, a screw for compressing the resistance member, a plate spring resting on the ledges in said body member for urging said screw in one direction to take up back lash and a bowed spring at one side of said resistance member for causing a progressively increasing pressure to be applied to the compression member by the screw.

3. In a device of the character described, a body member of insulating material and having a recess therein, a metallic plate in said recess, a terminal member permanently connected to said plate and extending to the outside of the body, a compression resistance member in the recess in said body member, a metallic base plate and a metallic face plate on opposite sides of said body member, a second terminal electrically connected to one of said plates, said last mentioned terminal being electrically connected to one side of said resistance member and said first mentioned terminal being connected to the opposite side thereof.

HAROLD P. DONLE.
